(57) **CLAIM**

The ornamental design for a drawer side panel, as shown and described.

DESCRIPTION

FIG. 1 is a perspective view of a drawer side panel, showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 is an enlarged fragmentary view of left side of the perspective view of FIG. 1.

All broken line portions of the figure drawings are included to show portions of the article that form no part of the claimed design.

1 Claim, 4 Drawing Sheets

FIG. 2

FIG. 3
